COVERED LADLE

Max W. Goldberg and Wallace W. Drissen,
Port Washington, Wis.

Application June 15, 1936, Serial No. 85,287

2 Claims. (Cl. 22—81)

This invention relates to improvements in covered ladles, and is a continuation in part of application Serial No. 73,829, filed April 11, 1936.

Heretofore, in foundry practice, it has been customary to utilize relatively small sized ladles which hold only a limited quantity of molten metal. Necessarily, therefore, these ladles must be frequently refilled and a large number kept in constant use in order to handle mold requirements. Thus, a relatively large number of attendants are needed to take care of the plurality of small ladles, which results in high overhead. It has been impractical heretofore to utilize ladles of larger size as the large quantity of molten metal would radiate an excessive amount of heat, making it impossible for attendants to remain near enough to take care of the pouring operations. Furthermore, in view of the large capacity, the ladles could not be emptied rapidly enough to prevent solidification therein.

In applications Serial Nos. 746,042, 43,146, and 73,829 there are disclosed means rendering the employment of large ladles entirely practical through the use of an insulated protecting cover and through the use of means for facilitating the opening and closing of said cover. The present invention relates more particularly to the cover itself and to the manner of insulating the same.

The insulation of the ladle covers has occasioned considerable difficulty heretofore. Fire brick is a desirable insulating material, but when a fire brick is made of the exact size of the cover, it is found that the difference in coefficient of expansion between the metal forming the cover proper and the fire brick forming the lining therefor sets up stresses which result in breakage of the lining. Furthermore, due to the fact that these ladles and covers are furnished in a wide assortment of sizes, it is impractical and costly to have fire brick of the exact size and shape for each of the various sizes of covers.

It is an object of the present invention to provide an improved lining of insulating material for ladle covers wherein the majority of the lining is composed of fire brick and wherein other material is employed around the fire brick in such a way as to readily adapt a slab of fire brick of one size for use in lining covers of various sizes, the joint between the fire brick and other material permitting a normal amount of expansion to take place without disrupting the cover.

A more specific object of the invention is to provide in combination a ladle, a metallic cover therefor having depending edge flanges, insulating brick of less size than the cover positioned adjacent the inner side thereof, refractory material of different composition than said brick filling the spaces between said brick and cover flanges, and metallic securing means extending through

the brick and cover to further hold the brick in position.

A further object of the invention is to provide an improved method of lining flanged covers including the steps of inserting fire brick of less size than the cover adjacent the inner side thereof, and filling the spaces between said brick and cover flanges with refractory material of different composition than said brick.

A still further object of the invention is to provide a method of lining flanged covers as above described, including the additional step of tapering the side edges of the slab of fire brick so that when the refractory material is packed between said tapered edges and the cover flanges, there will be an interlock to hold the two materials in position.

With the above and other objects in view, the invention consists of the improved covered ladle and all its parts and combinations as set forth in the claims and all equivalents thereof.

In the accompanying drawing illustrating one complete embodiment of the preferred form of the invention;

Fig. 1 is a plan view of the improved ladle showing the cover in closed position, the full line position of the operating handle showing how said handle is used to move the cover, and the dot-and-dash line position of the cover handle showing how said handle is used to lock the cover in closed position;

Fig. 2 is a side elevational view of the ladle, the dot-and-dash lines showing the cover in open position;

Fig. 3 is a fragmentary sectional view taken 35 on line 3—3 of Fig. 1; and

Fig. 4 is a bottom view of the cover alone.

Referring more particularly to the drawing, the numeral 5 designates a ladle of desired form. In view of the fact that the ladles comprehended by the present invention are of relatively large size, it is desirable that the same be insulated, preferably in the manner disclosed in co-pending application, Serial No. 47,560.

The ladle is preferably formed with an up-standing circular rim 6, with a pouring spout 7 and with side trunnions 8. A bail frame 9 includes side bails having hook-shaped lower ends 10 for engagement with the trunnions 8, and an upper transverse bar 11.

Guiding members 12 which are preferably tubular in form, are suitably secured to upper side portions of the ladle as at 13 and 14, and said members are disposed in an inclined position as is clear from Fig. 2. One of the guiding members 12 may be provided with a tubular extension 15 for a purpose to be hereinafter described.

The ladle cover designated generally by the numeral 16, comprises a top disc of metal 17 and a surrounding depending flange 18. The front of

the cover is preferably straight as at 19, and the rim 18 is tapered in the front as at 20 so that an operator standing at the rear of the ladle may at all times see the spout while pouring is being 5 accomplished. If the rim portion 20 were vertical, it would, in some positions, obstruct the attendant's view.

Welded to opposite sides of the cover toward the rear thereof are lateral extensions 21, and to 10 each of these extensions one end of a rod 22 is rigidly secured. The rods normally extend at an incline corresponding to the incline of the guide tubes 12, said rods being slideable in the tubes as is clearly indicated in Fig. 2.

15 At the rear of the cover is a short section of horizontally disposed metal tubing 23, and a handle 24 having a projection 25 at its outer end which may be engaged with the tube 23 in the manner shown in Fig. 1, facilitates movement of 20 the cover from the full line position of Fig. 2 to the dot-and-dash line position therein and vice versa. Inasmuch as it is desirable to normally limit the opening movement of the cover, the front of the latter is provided with an upstanding stop 26 which is engageable with the cross bar 11 of the bail frame, as shown in the dot-and-dash line position in Fig. 2.

It may at certain times be desirable to entirely 30 remove the cover. In the present arrangement the parts are so arranged that when the ladle is tilted rearwardly the stop 26 will fail to engage the cross bar 11, thereby permitting complete 35 removal of the cover and complete withdrawal of the rods 22 from the guiding tubes 12.

35 The cover may also be formed with a projecting lug 27 having its outer end apertured as at 28. The lug is so positioned on the cover that when the cover is in the closed position shown in Figs. 1 and 2, the aperture 28 will register with 40 the tubular extension 15 of the guiding member 12. When the cover is thus closed, the extension 25 of the handle 24 may be inserted into the aperture 28 and extension 15 to positively lock 45 the cover in closed position; thus the handle 24 serves the dual purpose of facilitating movement of the cover and locking thereof.

The insulation of the ladle covers has occasioned considerable difficulty heretofore. Fire brick is a desirable insulating material, but when 50 a fire brick is made of the exact size of the cover, it is found that the difference in coefficient of expansion between the metal forming the cover proper and the fire brick forming the lining therefor sets up stresses which result in breakage 55 of the lining. Furthermore, due to the fact that these ladles and covers are furnished in a wide assortment of sizes, it is impractical and costly to have fire brick of the exact size and shape for each of the various sizes of covers.

60 By referring to Fig. 3, it may be seen that there is fire brick 29 inserted in the cover and that said brick is substantially less in diameter than the cover. The fire brick is also preferably formed with bevelled side edges 30 and with a 65 plurality of recesses 31 in its lower face, communicating with bores 31' extending through the fire brick. In order to line a cover in the manner disclosed in the present invention, a thin layer of fire clay is spread on the upper surface 70 of the fire brick 29 and the brick is pressed against the inner surface of the cover top 17. Bolts 32 are then passed through the holes 31' 75 in the fire brick and through registering apertures in the cover portion 17, the heads of the bolts being received in the recesses 31. Nuts 33

are then threaded on to the bolts and tightened to hold the fire brick in position. Next fire clay or other refractory material is packed while in plastic condition between the edges of the fire brick and the cover rim as at 34 and permitted 5 to harden. Due to the bevel 30 on the fire brick, interlocking will take place between the edges of the fire brick and the hardened refractory material 34 to hold the two materials in position. After the bolts are in place it is desirable to 10 fill the recesses 31 with refractory material as at 35. It is also preferred to weld or otherwise secure a ledge 36 in position below the refractory material 34.

The joint formed at 30 between the fire brick 15 and the fire clay will permit a normal amount of expansion to take place in the lining without disrupting the cover. In addition, it will be noted that there is clearance between the sides of the bolt holes 31' and the bolts to allow for a certain amount of shifting of the fire brick during 20 expansion thereof.

With this method of lining, it is apparent that one size of fire brick 29 may be readily adapted for use in various sizes of covers, it being merely 25 necessary to utilize more or less of the refractory material 34 as an edge filling.

It is apparent that the cover and associated mechanism permits the cover to be readily opened and closed by manipulation of the handle 24, and 30 that the cover can be further locked in position through use of the same handle. Due to the fact that the lower portion 37 of the cover rim overlaps the rim 6 of the ladle, it is apparent that a straight rearward sliding movement of the 35 cover to open the same would not function. Due however, to the use of the inclined guiding tubes 12 and cooperating inclined rods 22, it is apparent that the cover is simultaneously raised, so that the flange portions 37 clear the rim 6, while 40 the cover is being moved rearwardly.

Although only one form of the invention has been shown and described, it is apparent that various changes and modifications may be made without departing from the spirit of the invention, and all of such changes are contemplated 45 as may come within the scope of the claims.

What we claim is:

1. A metallic ladle cover having depending edge flanges, insulating brick comprising a single slab 50 of less size than the cover positioned adjacent the inner side thereof, refractory material of different composition than said brick filling the spaces between said brick and the cover flanges, and a surrounding ledge extending inwardly from 55 the lower portion of the cover flanges below the refractory material to maintain the latter in position, the brick being of such size that it can be inserted from the bottom of the cover notwithstanding said ledge, and means for securing 60 the brick to the cover.

2. A metallic ladle cover having depending edge flanges, insulating brick comprising a single slab of less size than the cover and having tapered side edges with its smallest surface positioned 65 against the inner side of the cover, hardened refractory material of different composition than said brick filling the spaces between the edges of said brick and the cover flanges, and means for securing the brick to the cover whereby the tapered edges of the brick lock the refractory material in place.
